UNITED STATES PATENT OFFICE.

WILLIAM M. ROSSITER, OF SUNBURY, PENNSYLVANIA.

CURTAIN-POLE.

1,112,159.

Specification of Letters Patent. Patented Sept. 29, 1914.

Application filed December 2, 1913. Serial No. 804,265.

To all whom it may concern:

Be it known that I, WILLIAM M. ROSSITER, a citizen of the United States, residing at Sunbury, in the county of Northumberland and State of Pennsylvania, have invented 5 certain new and useful Improvements in Curtain-Poles, of which the following is a specification, reference being had therein to the accompanying drawing.

10 This invention relates to a curtain pole and the principal object of the same is the production of a hollow telescopic pole which is adapted to carry a stick in the interior of the same for supporting the curtain.

15 Another object of the invention is the production of a simple and efficient means carried by the pole for retaining the balls upon the end portions of the poles, thereby preventing the curtain carrying stick from 20 moving from the interior of the pole.

In the accompanying drawing; Figure 1 is a front elevation of the complete device showing the same supporting the curtains. Fig. 2 is a side elevation of the complete 25 device as carried by a window casing, portions of the same being shown in section. Fig. 3 is an enlarged detailed section showing a portion of the device showing the manner of securing the ball upon each section or end of the pole. Fig. 4 is a fragmentary detailed perspective view of the 30 pole and one bracket. Fig. 5 is a transverse section taken through the pole and curtain stick. Fig. 6 is a detailed perspective view 35 of a slidably mounted curtain pole supporting bracket.

Referring to the accompanying drawing by numerals, 1 designates the usual window casing having at its upper portion the molding 2. The bracket which is used in connection with this device for supporting the poles comprises a finger 3 having a downwardly bent spur 4 which is struck from the body portion of the finger so as to dig into the molding 2 for supporting the finger. 45 A diagonal arm 5 is provided at its upper portion with an integral sleeve 6, this sleeve 6 being fixedly secured to the finger 3 by means of the rivet 7. The lower end of 50 this arm 5 terminates in the coiled portion 8 which bears upon the casing 1 for supporting the forward portions of the arm 5 and finger 3 at a spaced distance from the casing 1. A vertical brace 9 is provided 55 with the angularly bent feet 10 and 10', which are secured to the arm 5 and finger 3

thereby holding the arm 5 and finger 3 in a spaced relation to each other and in such a manner as to allow the same to efficiently operate.

It will be obvious by referring to Fig. 1 that a bracket as above described may be supported adjacent each side of the casing 1 for supporting the end portions of the pole. This curtain pole is formed of a 60 plurality of sections which are adapted to telescope, each section being hollow and having at its lower section a longitudinal slot 11 through which the curtain is adapted to pass. The edges of the pole 12 adjacent 65 the slot 11 are rolled as clearly disclosed at 13 in Figs. 2 and 4. The curtain pole 12 which comprises the sections is positioned within the sleeves 6 of the brackets for the purpose of supporting the pole. A stick 14 70 is adapted to be positioned within the pole 12 and carry the curtains 15, as clearly disclosed in Fig. 5. For the purpose of retaining this stick 14 within the pole 12, the 75 balls which are carried at each end of the pole are provided with means for efficiently and securely supporting the same in their correct position. Each ball is hollow and comprises a plurality of sections 16, one of the sections being provided with an opening 17. A retaining plug is fixedly secured 80 within each ball and comprises an elongated body 18 which is held in position by means of the screw 19 passing through one of the sections 16 and engaging the body. This 85 body extends through the opening 17 and terminates in an enlarged head 20 having a rounded inner end 21. This head 20 is adapted to be forced within the interior of the pole 12 so as to slightly expand the 90 same and thereby efficiently support the ball upon the end portion of the pole and at the same time retain the stick 14 within the 95 interior of the pole.

A sliding bracket is adapted to be carried by each arm 5 for the purpose of supporting a secondary curtain pole. This 100 sliding bracket comprises a circular collar 22 from which the integral L-shaped lips 23 extend. These lips 23 are adapted to 105 overhang the arm 5 for supporting the sliding bracket in engagement with the arm. By referring to Fig. 4, it will be noted that the arm 5 is provided with the notch 24 for allowing the lips to be placed in engagement 110 with the arm.

From the foregoing description it will be

seen that a simple and efficient device has been produced for supporting a curtain which is provided with detachable means engaging the window casing for efficiently supporting the pole and also with means for preventing the curtain stick from moving from the interior of the pole.

What is claimed, is:—

A device of the class described comprising a hollow curtain pole having a longitudinal slot in its lower portion, means for supporting said pole, said pole adapted to carry a stick and allow a curtain carried by said stick to pass outwardly through said slot, a ball adapted to be carried upon each end of said pole, a retaining plug carried by

each of said balls, each plug comprising an elongated body terminating in an enlarged head having a rounded inner portion, said enlarged head adapted to be positioned within the interior of said pole and slightly expand the same for holding said ball in engagement therewith whereby the stick carried within said pole will be prevented from becoming accidentally removed from the interior of the same.

In testimony whereof I hereunto affix my signature in presence of two witnesses.

WILLIAM M. ROSSITER.

Witnesses:

EARL M. ROUSH,
GEO. E. DEPPEN.
